UNITED STATES PATENT OFFICE.

DAVID McNAIR, OF BOSTON, MASSACHUSETTS, ASSIGNOR TO ROXBURY CARPET COMPANY, OF SAME PLACE.

DESIGN FOR CARPET.

SPECIFICATION forming part of Design No. 11,950, dated August 17, 1880.

Application filed July 21, 1880. Term of patent 3½ years.

To all whom it may concern:

Be it known that I, DAVID McNAIR, of Boston, in the county of Suffolk and State of Massachusetts, have invented a new and original Design for Carpets, of which the following is a specification.

The nature of my design is fully shown in the accompanying photographic illustration, forming a part of this specification.

10 The design is composed of the octagonal figures A, ornamented by floral designs and surrounded by Grecian border-work, the figures B, ornamented by floral designs, the superposed figures C D E, variously ornamented, and the irregular ornamented figures F G H 15 I J.

I claim—

The design for a carpet, substantially as shown and described.

In testimony whereof I have signed my name to this specification, in the presence of two subscribing witnesses, this 17th day of July, A. D. 1880.

DAVID McNAIR.
